UNITED STATES PATENT OFFICE.

GUSTAV A. KRUTTSCHNITT, OF NEWARK, NEW JERSEY.

DESIGN FOR A BOX OR RECEPTACLE.

SPECIFICATION forming part of Design No. 33,614, dated November 27, 1900.

Application filed October 30, 1900. Serial No. 34,953. Term of patent 3½ years.

To all whom it may concern:

Be it known that I, GUSTAV A. KRUTTSCHNITT, a citizen of the United States, residing at Newark, in the county of Essex and State of New Jersey, have invented and produced a new and original Design for Boxes or Receptacles, of which the following is a specification, reference being had to the accompanying drawings, forming part thereof.

- 10 Figure 1 is a plan view of the box or receptacle, showing my design. Fig. 2 is a section through the lid or cover of the box on the line X X of Fig. 1. Fig. 3 is a rear side view of the box. Fig. 4 is an end side view of the

15 box.

The leading feature of my design consists of the border ornamentation along the outer portions of the substantially flat face and overlapping edges of the lid of the box, substantially as shown in the drawings.

20 In the drawings, B designates the lid or cover of the box A, which has a substantially flat face, as shown in Figs. 2, 3, and 4, and which face, as illustrated in Fig. 1, bears the 25 ornamental border comprising the ornamental scroll figure C and the ornate wavy defining border-line D. The scroll figure C has the appearance of being in relief and as 30 possessing a delicate mottled surface and bears at intervals the disk representations C',

which have the appearance of possessing clean bright surfaces.

The substantially flat side walls E of the box or receptacle bear the central ornamentation F, possessing the same appearance as the scroll figure C and surrounded by the embellishments F'. The corners of the box are joined to present the ornamental overlapping portions H and have the corner ornamentations I, the latter possessing the same appearance as the scroll figure C and corresponding in embellishment to the central ornamentations F, while the overlapping edges B' of the lid B bear the ornamental scroll figure C, also provided with the spotted appearance 45 C', in the representation of disks, at intervals.

The lid or cover B and the rear side walls E' are so joined as to present one continuous ornamental hinge effect K, as shown. 50

What I claim is—

The design for a box or receptacle, substantially as herein shown and described.

Signed at Newark, in the county of Essex and State of New Jersey, this 10th day of October, 1900.

GUSTAV A. KRUTTSCHNITT.
